UNITED STATES PATENT OFFICE.

ERNEST A. OVERSTEDT, OF BELOIT, WISCONSIN, ASSIGNOR TO C. MATTISON MACHINE WORKS, OF BELOIT, WISCONSIN, A CORPORATION OF WISCONSIN.

APPARATUS FOR MARKING KNIFE-BLANKS.

1,191,989.

Specification of Letters Patent. Patented July 25, 1916.

Application filed September 22, 1915. Serial No. 51,945.

To all whom it may concern:

Be it known that I, ERNEST A. OVERSTEDT, a citizen of the United States, residing at Beloit, in the county of Rock and State of Wisconsin, have made certain new and useful Improvements in Apparatus for Marking Knife-Blanks, of which the following is a specification.

The cutter-heads of wood-turning and similar machines are equipped with knives set at an angle with relation to the axis of the cutter head. The cutting edges of the knives therefore are not of the same form as the coves, beads or other shapes to be imparted to the work. Because of the inclined position of the knife, the edge of the knife is longer than the cove, bead or other form produced by the knife.

In making cutter-knives, cut-and-try methods have heretofore been used, the blank being first ground to a rough approximation of the correct form, then rotated alongside a sample or pattern of the piece to be turned, then subjected to further grinding, again compared with the pattern, and so on until the required outline is imparted to the knife.

The object of this invention is to provide an apparatus whereby the outline required to produce the desired work may be quickly and accurately marked upon the knife blank, so that the proper conformation may be imparted to the blank at substantially a single grinding.

In the accompanying drawings, Figure 1 is a transverse vertical sectional view of an apparatus embodying the features of my invention, the view being taken in the plane of dotted line 1-1 of Fig. 2. Fig. 2 is a top plan view of said apparatus. Fig. 3 is a view looking from the right-hand side of Fig. 1. Fig. 4 is a view of one of the end supports for the arbor of the machine. Fig. 5 is a perspective view of a marking device comprised in the apparatus.

The apparatus comprises an arbor 1 upon which the cutter-head or sections of the cutter-head may be mounted. Said arbor is rotatably supported in three bearing brackets 2, 3, and 4. The bearing bracket 2 is detachably secured in position by means of a bolt 5 in order that said bracket may be removed to permit of mounting and demounting the cutter-head.

While the apparatus may be used in con-

nexion with cutter-heads of various forms, I have herein shown a cutter-head comprising a hexagonal body *a* having longitudinal T-slots *b*. To the body *a* are secured diametrically opposite knife carriers *c*. The knives are secured to the knife carriers by means of bolts *d*.

Means is provided for supporting a pattern *P* at one side of the arbor and extending parallel therewith. Said pattern may be of any suitable construction, as, for example, a thin strip of hardwood having one edge shaped to correspond with the periphery of the work to be produced by the turning machine. The means for supporting the pattern *P* comprises, in this instance, two standards 6 and 7 having slots 8 to receive the ends of the pattern. The pattern is secured in place by means of thumb-screws 9. The pattern is held with its shaped edge at the side toward the cutter.

Below the pattern *P* is means for supporting a marking device. While said supporting means may be of any suitable character, I have herein shown a guide bar 10 secured to the standards 6 and 7. On the guide bar 10 is movably mounted a slide 11 shown in perspective in Fig. 5. Said slide comprises top and bottom plates 12 which are adapted to fit slidably, but snugly, in contact with the upper and lower sides of the guide bar 10. The slide 11 is of such size as to permit it to slide and turn horizontally upon the guide bar 10, vertical movement, however, being impossible. Thus it will be seen that the slide is mounted so that it may turn in a plane parallel with the plane of the pattern.

The slide 11 has fixed thereto a vertically-extending tracer 13 adapted in the movements of the slide 11 to follow the shaped edge of the pattern *P*. The tracer 13 may consist of a wire or pin of small diameter so as to enter the angles and coves of the pattern.

The slide 11 is provided with a socket 14 in which a marker 15 may be secured by means of a set screw 16. The marker is axially alined with the tracer 13 and has a sharp point adapted to trace a line upon a knife blank secured to the cutter-head. In practice, the knife blank is coated with a suitable plastic material in which the marker 15 may trace a line indicating the form of the edge to be imparted to the knife. The

slide 11 may be provided with a handle of any suitable form for use in moving the tracer 13 along the edge of the pattern P. Herein I have shown two angular brackets 5 or handles 17.

In use, a pattern P is secured in the apparatus. A cutter-head section is then placed upon the arbor 1 opposite the part of the pattern which represents the form which the 10 knife is to cut. The knife blank having been coated with a plastic material, the operator moves the slide 11 along the bar 10, keeping the tracer 13 in contact with the edge of the pattern and turning the cutter-head so that the point of the marker 15 may 15 trace a line on the surface of the blank. The knife carrier *a* bearing the blank is then removed from the body *a*, and the blank ground to produce a cutting edge along the 20 line traced by the marker.

For convenience, the blank-marking apparatus herein described may be provided with means for supporting another pattern P' identical with the pattern P at the side 25 of the arbor 1 opposite to the pattern P. The ground blank may be attached to the body *a* and revolved past the pattern P' for the purpose of determining whether or not the grinding has been accurately done.

As the cutter-head is revolved at high 30 speed in the turning machine, it is necessary that the knives be securely fastened to the knife carriers. In order that the operator may apply both hands to the wrench while 35 tightening up the bolts *d*, I provide means to hold the arbor 1 stationary, which means consists of a pin 18 adapted to be placed in a transverse opening in the arbor, the end of the pin lying between lugs 19 on the 40 bearing bracket 4.

I claim as my invention:

1. An apparatus for marking knife blanks having, in combination, an arbor for rotatably supporting a cutter-head, means for 45 supporting a pattern extending longitudinally of the arbor, a slide supported for movement longitudinally of the pattern and arranged for limited turning movement in a plane parallel with the plane of the pattern, a tracer on the slide adapted to follow the pattern, and a marker on the slide adapted to engage a knife blank on the cutter-head.

2. An apparatus for marking knife blanks 55 having, in combination, an arbor for rotatably supporting a cutter-head, guide means extending parallel to the arbor, means for supporting a pattern extending

longitudinally of the guide means, a slide movable longitudinally of said guide means 60 and adapted to turn in one plane only, a tracer on the slide adapted to follow the pattern, and a marker on the slide adapted to engage a knife blank on the cutter-head.

3. An apparatus for marking knife blanks 65 having, in combination, an arbor for rotatably supporting a cutter-head, a guide member extending parallel with the arbor, means for supporting a pattern extending longitudinally of the guide member, a slide 70 movable along said guide member, a tracer on the slide adapted to follow the pattern, and a marker axially aligned with the tracer and fixed to the slide, said marker being adapted to engage a knife blank on the cutter-head.

4. An apparatus for marking knife blanks having, in combination, means for rotatably supporting a cutter-head, a guide member extending parallel with the axis of 80 the cutter-head, means for supporting a pattern extending longitudinally of the guide member, a slide movable along said guide member, a tracer on the slide adapted to follow the pattern, and a marker on the 85 slide adapted to engage a knife blank on the cutter-head.

5. An apparatus for marking knife blanks having, in combination, means for rotatably supporting a cutter head, means for supporting a pattern extending longitudinally of the axis of the cutter-head, a tracer movable along the pattern, and a marker fixed to the tracer and adapted to engage a knife blank on the cutter-head.

6. An apparatus for marking knife blanks having, in combination, means for rotatably supporting a cutter-head, means for supporting a pattern, a tracer movable along the pattern, and a marker axially aligned 100 with and connected to the tracer and adapted to engage a knife blank on the cutter-head.

7. An apparatus for marking knife blanks having, in combination, means for rotatably 105 supporting a cutter-head, means for supporting a pattern, a tracer movable along the pattern, and a marker connected to the tracer and adapted to engage a knife blank on the cutter-head.

In testimony whereof, I hereunto set my hand in the presence of two witnesses.

ERNEST A. OVERSTEDT.
